[57] CLAIM

The ornamental design for a chimney cap component, as shown and described.

DESCRIPTION

FIG. 1 is a front perspective view of a chimney cap component showing my new design;

FIG. 2 is a top plan view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a bottom plan view thereof;

FIG. 8 is a front perspective view of a chimney cap component, showing a second embodiment of my new design;

FIG. 9 is a top plan view of FIG. 8;

FIG. 10 is a right side elevational view of FIG. 8;

FIG. 11 is a left side elevational view of FIG. 8;

FIG. 12 is a front elevational view of FIG. 8;

FIG. 13 is a rear elevational view of FIG. 8;

FIG. 14 is a bottom plan view of FIG. 8;

FIG. 15 is a front perspective view of a chimney cap component, showing a third embodiment of my new design;

FIG. 16 is a top plan view of FIG. 15;

FIG. 17 is a right side elevational view of FIG. 15;

FIG. 18 is a left side elevational view of FIG. 15;

FIG. 19 is a front elevational view of FIG. 15;

FIG. 20 is a rear elevational view of FIG. 15; and

FIG. 21 is a bottom plan view of FIG. 15.

Fig. 3.

Fig. 2.

Fig. 4.

Fig. 5.

Fig. 6.

Fig. 7.

Fig. 8.Fig. 10.Fig. 9.Fig. 11.Fig. 12.Fig. 13.Fig. 14.Fig. 15.Fig. 17.Fig. 16.Fig. 18.Fig. 19.Fig. 20.Fig. 21.
